UNITED STATES PATENT OFFICE

WILHELM MAILAENDER, OF STUTTGART-CANNSTATT, GERMANY

ROTARY DEEP IMPRESSING PRINTING MACHINE

Application filed December 6, 1926, Serial No. 153,012, and in Switzerland November 8, 1926.

This invention relates to rotary deep impressing printing machines.

An object of the invention is to completely remove the color which remains upon the surface of the cylinder on raising the doctor or scraper so that smearing cannot take place.

The working tools used for this purpose besides the usual doctor or scraper comprise a second tool both of which work on the lower part of the cylinder and most conveniently at the lowest point thereof so that the colour removed by the doctor or scraper does not return back to the printing plate and cannot therefore obtain access to the cylinder space.

15 It flows directly from the doctor or scraper downwardly into the colour trough. The working tools are so controlled that on the one hand the doctor or scraper is applied to the plate before the beginning of printing and removed from the plate after the end of printing and on the other hand the second working tool is removed after passing the application point of the doctor or scraper and is again set into operation between the end of printing 25 and the removal point of the doctor or scraper.

As the second working tool a stripping roller can be used which is rotated in a direction opposite to that of the cylinder, the upper surface thereof being of non-porous material, 30 as for example brass.

A stripping plate can be arranged on the doctor or scraper so as to remove the color therefrom. The arrangement is such that the 35 doctor or scraper does not come into contact with the stripping plate on rinsing or cleaning of the said doctor or scraper.

In order that the invention may be clearly understood and readily carried into effect, 40 reference is made to the accompanying drawing which shows diagrammatically and by way of example a constructional form in accordance with the present invention.

The figure shows in side view a constructional form of the machine.

A printing plate 2 is sprung or tensioned over the printing cylinder 1 and the said plate may be so constructed or of such a form that its ends abut against each other or the said 50 plate may be of such a form as to leave a space

3 in the cylinder and between the ends of the plate so that the plate 2 can be tensioned by means of a known arrangement which would be disposed in the cylinder space 3. The length of the printing surface of the cylinder plate 1 measured in the direction of the circumference of the cylinder is greater than the length of the paper such length being that required to permit of the application and removal of the doctor or scraper tool.

55 A scraper 4 for example of the usual form is provided for the removal of the superfluous colour. The tool 4 according to the present invention works on the lower half of the printing cylinder 1 such position being conveniently near the lowest position of the cylinder, but it should be clearly understood that the position may be varied substantially.

60 The doctor or scraper 4 according to the present invention is applied to the plate 2 before the beginning of the engraved portion or design has passed the doctor or scraper and the removal of the doctor or scraper in the arrangements shown, is effected after the end of the engraved portion or 65 design has passed the said doctor or scraper, so that the doctor or scraper 4 sweeps over the whole length of the design.

70 The usual colour coating roller 11 serves for coating the printing plate 2 with colour 80 to which colour coating roller the colour is delivered from the colour trough 12 by means of a colour carrying roller 13. The colour removed by the doctor or scraper 4 is introduced into the colour containing receptacle 85 by means of a light sheet metal plate. The rollers 11 and 13 are rockably and disengageably arranged and they are supported for this purpose in lever like bearings 14 which are rockable about the axis 15 and are 90 under the influence of the spring. The levers 14 are controlled by an eccentric 16 on which a roller on the lever 14 runs. The colour coating roller 11 is so controlled that it is applied shortly before the beginning 95 of the design and is removed immediately after the end of the design.

Near the beginning of the design on the plate 2 the coating roller 11 automatically 100 comes into contact with the said plate and

color is applied thereon, the roller remaining in contact with the plate until the end of the design so that the whole design is colored.

The stripping roller 24 consists on its upper surface of non-porous material for example brass. It is pressed for example by a spring 25 constantly against the plate 2 or the eccentric 27 whilst it presses down the one end of the bearing 26 of the roller 24 formed as a double armed lever, and forces this yieldingly upward against the plate 2. The application and removal of the roller 24 is controlled in the known manner by an eccentric 27 on which a roller 28 of the bearing 26 runs and thereby applies and removes the roller 24. It is driven in any suitable manner from the drive of the cylinder 1 through intermediate gear wheels 29.

The colour acquired from or taken up by the roller 24 is stripped therefrom by a doctor 30 or scraper and passes therefrom into the colour trough 31.

The doctor or scraper 4 mounted on the yieldable holder 32 is provided with a stripping plate 33 having at the sides upstanding guides or plates which prevent the color escaping laterally, and guides the color so that it flows into the color trough 12 into which the color roll 13 dips.

30 What I claim is:—

1. A rotary deep impressing printing machine, including a scraper for removing the greater part of the color strip, a stripping roller for the removal of the remainder of the color strip, said roller at the line of contact being movable in a direction opposite to the direction of movement of the cylinder.

2. A rotary deep impressing printing machine, including a scraper for removing the greater part of the color strip, a stripping roller provided for the removal of the remainder of the color strip, means for moving said stripping roller at the line of contact in a direction opposite to the direction of movement of said cylinder, and a special doctor or scraper for freeing said stripping roller from color.

3. A rotary deep impressing printing machine, including a scraper for removing the greater part of the color strip, a stripping roller provided for the removal of the remainder of the color strip, means for moving said stripping roller at the line of contact in a direction opposite to the direction of movement of said cylinder, a special doctor or scraper for freeing the stripping roller from color, and a color holder or trough disposed under the stripping roller, so that the latter runs permanently in the color in the said color trough or holder.

4. A rotary deep impressing printing machine, including a stripping roller provided for the removal of the color strip and moving at the line of contact in the direction opposite to the direction of movement of said cyl-

inder, a special doctor or scraper for freeing the stripping roller from color, a main stripper comprising a stripping plate and a holder therefor.

5. A rotary deep impressing printing machine comprising means for removing the greater part of the color strip, a stripping roller for the removal of the remainder of the color strip, said roller at the line of contact being movable in a direction opposite to the direction of movement of the cylinder.

6. A rotary deep impressing printing machine comprising a single means for removing the greater part of the color strip, a stripping roller for the removal of the remainder of the color strip, said roller at the line of contact being movable in a direction opposite to the direction of movement of the cylinder and said single means for removing the greater part of the color strip being located at the lower part of the lower half of the cylinder.

7. A rotary deep impressing printing machine comprising means for removing the greater part of the color strip, a stripping roller for the removal of the remainder of the color strip, and means for operating said roller in timed cooperation with said means for removing the greater part of the color strip.

8. A rotary deep impressing printing machine comprising means for removing the greater part of the color strip, a stripping roller for the removal of the remainder of the color strip, means for operating said roller in timed cooperation with said means for removing the greater part of the color strip, and means for moving said roller at the line of contact in a direction opposite to the direction of movement of the cylinder.

In testimony whereof I affix my signature.
WILHELM MAILAENDER, ENGINEER.
